UNITED STATES PATENT OFFICE.

HARRY TAYLOR, OF HAMILTON, ONTARIO, CANADA, ASSIGNOR TO HORACE WELLESLEY BURRITT, OF TORONTO, CANADA.

BOAT-PROPELLER.

1,067,385.

Specification of Letters Patent. Patented July 15, 1913.

Application filed March 26, 1912. Serial No. 686,269.

To all whom it may concern:

Be it known that I, HARRY TAYLOR, a subject of the King of Great Britain, of the city of Hamilton, in the county of Wentworth, 5 in the Province of Ontario, Canada, have invented certain new and useful Improvements in Boat-Propellers, of which the following is the specification.

My invention relates to improvements in boat propellers in which reversing blades are employed and the object of the invention is to provide means for easily reversing the blades of the propeller and to so improve the construction of the propeller as to prevent 10 breaking and consequent loss of the blades and it consists essentially of a propeller shaft, a slideable sleeve held upon the shaft and having an annular groove therein, a vertical divided hub connected to the shaft at 15 its outer end and keyed to the slideable sleeve, blades turnably held within the hub having crank pins extending into the aforesaid annular groove and an encircling rim in which the outer ends of the blades are journaled as 20 hereinafter more particularly explained by the following specification.

Figure 1, is a side elevation of my device. Fig. 2, is a vertical longitudinal section. Fig. 3, is a vertical cross section. Fig. 4, is 25 an enlarged detail of the hub partially broken away and in section.

In the drawings like letters of reference indicate corresponding parts in each figure.

A is the propeller shaft.

35 B is the hub comprising two members B' and B² connected together in a vertical plane by bolts B³. Each hub member B' and B² is provided with semi-circular edge recesses B⁴ and B⁵ having ribs B⁶ extending around 40 the same intermediately of the height of the recesses. The hub member B' is connected to the propeller shaft A by a key A' and by an end nut A² threaded onto the end of the propeller shaft and locked thereon by a cross 45 pin A⁴.

C are the propeller blades provided at their outer ends with trunnions C' and at their inner ends with enlargements C² having annular grooves C³ therein. The enlargements C² fit into the recesses B⁴ and B⁵ so 50 that the tongues B⁶ thereof fit into and around the annular grooves C³ so as to turnably hold the blades C in the hub B.

D is an operating sleeve encircling the

shaft A and slidably extending into the hub 55 B. The outer end of the sleeve within the hub is provided with an enlargement D' having an annular groove D² therein. The enlargements C² of the blade C are provided with rollers C⁴ journaled on crank pins C⁵ 60 indicated by dotted lines in Fig. 3. The rollers C⁴ extend into the annular groove D² as indicated particularly in Figs. 2 and 3.

E is a feather key secured within the hub and extending into a groove E' in one of the 65 annular flanges of the enlargement D' forming the groove D².

It will be seen by operating the sleeve D longitudinally that the groove D² engaging with the rollers C⁴ serve to swing the blades 70 C around in their bearings formed by the enlargement C² and trunnion C' either into the reverse or forward position. It will also be seen that by journaling the blades at their inner end in the hub and at the outer end in 75 the rim that a secure support will be formed for the blades which will not allow the blades to break away as is the case where the blades are only supported at their inner ends.

In former constructions when reversing the blades the whole hub is slidably moved on the propeller shaft against the torsional strain of the hub due to the water pressure on the blades. In my form the hub is solidly 85 connected to the propeller shaft and the blades alone are turned against the pressure thus rendering the operation of my device more easy to the operator.

What I claim as my invention is:

1. A propeller comprising a hub secured to the propeller shaft, a sleeve slidably supported upon the shaft having an annular groove therein, an encircling rim, blades journaled at their inner ends in the hub and 95 at their outer ends in the rim, and crank rollers journaled on the inner ends of the blade members extending into the annular groove of the sleeve as and for the purpose specified.

2. A propeller comprising a hub secured to the propeller shaft, a sleeve slidably held upon the propeller shaft and extending within the hub and feathered to the hub, an encircling rim, propeller blades journaled at 105 their outer ends in the rim and at their inner ends in the hub, and crank rollers extending from the inner end of each blade member

into the annular groove of the longitudinally slideable sleeve, as and for the purpose specified.

3. A propeller comprising a cross divided hub having semi-circular tongued recesses in the opposing edges thereof, an encircling rim, blade members provided with trunnions at their outer ends journaled in the rim and enlargements at their inner ends having annular grooves fitting the tongued recesses of

the hub, crank rollers journaled on the inner enlargements of the blades, and a longitudinally slideable sleeve having an annular groove into which the rollers extend and slidably held on the propeller shaft, as and for the purpose specified.

HARRY TAYLOR.
